WITNESS:

H. R. Jones
INVENTOR
BY *Victor J. Evans*

ATTORNEY

UNITED STATES PATENT OFFICE.

HARRY R. JONES, OF MARCUS HOOK, PENNSYLVANIA.

POWDER PUFF.

Application filed April 2, 1923. Serial No. 629,460.

To all whom it may concern:

Be it known that I, HARRY R. JONES, a citizen of the United States, residing at Marcus Hook, in the county of Delaware and

5 State of Pennsylvania, have invented new and useful Improvements in Powder Puffs, of which the following is a specification.

The object of this invention is to produce a powder puff in the nature of a pouch 10 having frames secured to the open ends thereof and means for clamping the frames together, one of the sides of the pouch being of soft material that is practically non-porous and with a light nap such, for instance, as chamois skin, the other side being of soft, fluffy pervious material such as eiderdown, the pouch designed to receive therein a quantity of powder, the chamois being designed to remove the gloss from the 15 user's face and the eiderdown permitting the powder to pass therethrough to apply the same on the face of the user.

20 The drawings which accompany and form part of this application illustrate a satisfactory embodiment of the improvement reduced to practice, and in which:—

Figure 1 is a front elevation of the improvement.

Figure 2 is a rear elevation thereof.

30 Figure 3 is a sectional view on line 3—3 of Figure 1.

The body of my improvement is round in plan and is in the nature of a pouch. The pouch comprises two faces of different material, one of the faces 1, being preferably of chamois skin, or some soft textile, with light nap and which is practically non-porous. The second face 2 is of some soft fluffy material pervious, but not having 35 large pores. This face is preferably in the nature of a sheet of eiderdown. Both sheets 1 and 2 are stitched together and then

40 turned inside out so that no stitches will appear on the completed article. The open edges provided by the sides of the pouch have secured thereon metal frames 3 which 45 have their ends hingedly connected, as at 4, and both of the frames are centrally provided with interengaging latching means such as curved fingers having ball heads, as 50 illustrated by the drawings.

With my improvement a determined quantity may be arranged in the pouch and because of the close weave of the face 2 none of the powder will escape when pressure is 55 exerted against this face of the pouch.

It is of course to be understood that the latched frames hold the pouch closed. The face 1 of the pouch is employed for removing gloss or perspiration from the face of 60 the user while a light tap delivered on the face of the user by the side 2 of the pouch will cause a determined quantity of powder to permeate through the pores of this face 65 of the pouch, and the same may be rubbed on the face of the user by the fleecy outer covering on this side or face of the pouch.

Having described my invention I claim:—

A powder puff comprising a pair of members of similar outline stitched together 70 along part of their edges to provide a pouch having a filling opening, one of said members being of soft non-pervious material and the other of said members being of pervious material, a frame member secured to 75 the free edge of each of said members at said filling opening, said frame members at their ends hinged together, and said frame members having coating means for holding the frame members in contact with the filling opening closed.

80 In testimony whereof I affix my signature.

HARRY R. JONES.
